[57] ABSTRACT

A reed relay switch consists of a pair of low reluctance, ferromagnetic, flattened reeds, which are hermetically sealed into a glass tube. The ferromagnetic material extends out of the glass tube and to a juncture with interconnecting conductors to external circuits. These junctures are usually of dissimilar metals and generate thermal EMF's. A thermally conductive electrical insulating body is provided and the connections are made at either side of this body so that the thermal EMF's produced by the thermally active junctions tend to cancel each other and reduce the thermal EMF across the reed relay.

REED RELAY HAVING LOW THERMAL EMF

BACKGROUND OF THE INVENTION

A reed relay consists of two or more metal reeds which are enclosed in a hermetically sealed glass capsule. The reeds are made from nickel-iron, a magnetically soft alloy, that retains only little magnetism. The reeds which form the switch are activated by an externally applied magnetic field and conventionally the capsule is placed within a solenoid which provides the magnetic flux. Generally the flexible metal reeds are held apart except in the presence of the magnetic field. As mentioned before, the reeds are composed of a nickel-iron alloy, one suitable alloy being sold under the tradename of "Niron" and extensions of this reed structure are brought out through the glass enclosure to form the ends of the reed switch. To make a connection to an external circuit, it is almost universal to utilize the material which is copper although oftentimes the material is tinned copper or gold or silver plated copper, and in certain applications may even be silver or gold. The interconnection material generally being chosen to avoid any further thermoelectric junctions with the external circuitry. At the points where the interconnection material and the magnetic material make contact, junctions of dissimilar materials are made, and these junctions generate thermal EMF's due to the thermoelectric effect. For example, typical reed relay switches produce thermal EMF's ranging from 10 to 100 microvolts, and thermal differences of this magnitude cause serious problems when microvolt signals must be switched. One of the problems has been the fact that the two junctions are made on opposite ends of a switch capsule and, therefore, cannot be maintained at the same temperature, temperature differences of 1°C. sometimes giving rise to thermal EMF differences of 50 microvolt magnitude. Accordingly, in order to maintain an offset across the switch of less than 0.5 microvolts, the two thermal junctions must be less than 0.01°C apart.

It is known, for example, that the temperature differentials are created in a number of ways, such as by heat dissipated in the actuating coil or a solenoid, different convective air currents, external heat generators in the circuitry in which the switch is used and possibly some other factors not specifically mentioned. In the past there has been at least one attempt to correct this deficiency in a reed relay, and this has been disclosed in the Becker et al U.S. Pat. No. 3,456,216. The attempt that was made here was to serially connect a pair of reed switches in such a fashion that the thermal junctions were made at the same end of the body, and in this fashion temperature differentials would be substantially reduced. The main difficulty with this approach is the large size of the package that results and the fact that two switches must be used for one circuit.

SUMMARY OF THE INVENTION

It is, therefore, the main object of this invention to provide a technique by which practically any reed switch can be modified to produce a reed relay having a thermal EMF of less than 1 microvolt and yet maintain the package size as small as has been practical in the past. This object is achieved by diminishing the temperature difference between the two ferro magnetic alloy-copper junctions by the simple expedient of main-

taining the two junctions at the same temperature by attaching them both to opposite sides of a thin thermally conductive electrical insulator. When a high degree of accuracy is desired, it is further possible to remove the junctions from all heat sources, that is, by physically separating the junctions from the solenoid drive coil and prevent that coil from contributing to a temperature differential. For example, the ferro magnetic alloy-copper junctions can be placed on top of the coil by extending the ferro magnetic alloy leads a sufficient distance to place the junctions substantially midway along the coil over the reed switch.

DESCRIPTION OF THE DRAWINGS

- 15 FIG. 1 is a perspective view partly in section of a reed relay manufactured in accordance with the invention;
 FIG. 1A is a diagrammatic view of a modified configuration;
 20 FIG. 1B is a diagrammatic view of another modified configuration;
 FIG. 2 is a sectional view taken along lines 2-2 of FIG. 1 illustrating the thermally conductive electrical insulating body with the leads soldered thereto;
 25 FIG. 2A is a sectional view of a modification of the showing of FIG. 2;
 FIG. 2B is a perspective view of a different modification of FIG. 2;
 FIG. 3 is a sectional view of an encapsulated low thermal EMF switch which may be actuated by any form of magnetic field; and
 FIG. 4 is a view of a modified form of switch.

DESCRIPTION OF THE PREFERRED EMBODIMENTS

35 Referring now to the drawings and particularly to FIG. 1, there is shown a reed switch 10 which consists of a pair of metal reeds 11, 12 enclosed within a hermetically sealed glass capsule 13. The reeds 11 and 12 are made from a nickel-iron alloy, Niron, for example, and have overlapping ends the form the contact surfaces, generally indicated at 14. Sometimes the contact surfaces are plated with a suitable metal to promote lower contact resistance and generally a chemically inert gas is enclosed in the capsule which further contributes to the maintenance of good contact properties. The glass capsule is surrounded by a magnetic operating means in the form of a coil or solenoid which may 40 be wound about a bobbin 15 which has a pair of spaced end walls 16, 17. If a bobbin is used it may be formed of a plastic material such as nylon or any other suitable non magnetic material and in all forms define an elongated housing in which the switch 10 is received and 45 suitably held in position as by elastic buffers or other devices indicated by the numerals 18. The coil 20 is normally wound with very fine copper wire of a size, voltage rating and a number of turns that will actuate the particular reed switch 10, which is mounted 50 therein. It is preferable that the coil be wound evenly and symmetrically to provide even dissipation of heat throughout its surface.

55 The nickel-iron alloy reeds which extend outwardly from the sealed capsule 13 may be said to have end portions thereof which shall be designated 22, 23. These end portions may have welded thereto as at 24, 25, portions of a lead material designated 26, 26' which

should also be of the same nickel-iron alloy as the reeds 11 and 12. Alternately, should it be desired, the end portions 22', 23' may be bent upwardly and should possibly terminate centrally above the housing as shown in FIG. 1A. If the lead material 26, 26' is used as illustrated in FIG. 1, it is preferable that this lead material be of a thin wire so that it does not conduct heat from the vicinity of the reed switch to the junction which will now be described.

At the top of the coil there is located nickel-iron copper junctions as at 30 and 30' (see also FIG. 2). These junctions are formed between the nickel-iron wires 26 and the interconnection material such as conductor member copper wires 31, 31' which have been stated as being copper for the sake of illustration but which also could be of other materials, such as copper plated with gold, tinned copper, pure gold, or pure silver wire and have been chosen as the material which will not create an additional thermal junction at the circuit into which the reed relay is to be inserted. It is preferable that the conductors 31, 31' be of a thin wire to avoid conduction of heat from the outside environment. It should be understood that for the purposes of this invention this thermal junction is not dependent upon any one material of conducting wire that leads from the switch, but can be of any material that forms a thermal junction with the nickel-iron alloy that forms part of the reed switch assembly. To maintain the two junctions 30 and 30' at the same temperature, they are attached to a thermally conductive electrical insulator designated 32. The two junctions 30 and 30' are attached to opposite sides of this insulator 32, and if the insulator is properly constructed, this can be done by simply soldering them to the opposite sides.

A junction which is alternate to FIG. 2 is shown in FIG. 2A where wires 26, 31 and 26', 31' are molded into a wafer 35 of thermally conductive electrical insulator. In FIG. 2B a further alternate is shown where the thermally conductive electrical insulator 32B has mounted thereon metal films 33B in spaced relation and the wires 26, 31 and 26', 31' are soldered to these metal films as at 34B thus placing the connections on the same side of the insulating body instead of on opposite sides as in FIG. 2.

As an example of a suitable insulator, beryllium oxide has proven to be an excellent material, although other materials with the desired properties are available, such as aluminum oxide Al_2O_3 , and boron nitride, BN. A suitable configuration for the insulator 32 and particularly one that is made from beryllium oxide which has a resistivity of 10^{16} ohm-cm and a thermal conductivity approaching that of some metals, is to first coat opposite sides of the chip with a molybdenum manganese film and then coat that film with a nickel film and then place a gold flash coating on the outside. If this is done and the proper film is provided, which film is generally designated 33 or 33B, solder such as 34 or 34B may completely hold the junction to the insulator 32 as well as making thermal contact with the insulator 32, 32A, 32B. Other thermally conductive materials may be used to establish thermal contact of the junctions and the insulator 32, 32A, 32B. It has been found that if the insulator 32 is made from beryllium oxide with the film flashings mentioned above that optimum size considering the best combination of elec-

trical and thermal properties is found with a chip that is 0.150 inches long, 0.080 inches high and 0.015 inches thick. Additionally, the solder which is used to secure the thermal junction to the insulator 32, is preferably of either the tin lead type or the cadmium tin type, the latter to be preferred when a higher performance is desired.

In FIG. 1B reference numeral with an "A" suffix have been used for slightly varied part configurations. Here the entire capsule 13A and thermally conductive electrical insulator 32A is within the coil 20A. The insulator should be oriented along a radius of the coil to equalize heat at either side thereof and in other respects the construction is equivalent to FIG. 1.

Referring to FIG. 3 of the drawings there is illustrated a self-contained low thermal EMF switch which can be actuated by any type of magnetic influence. This construction comprises a glass capsule 40 with a pair of reeds 41, 42 contained therein with the reeds extending outwardly of the capsule. The portions which extend outwardly of the capsule may either be bent back around into the center of the capsule so as to overlie the same or lead material 43, 43' secured respectively to each reed and then led back to substantially the center of the capsule at which point a connection is made with a conductor member 44 and 45 respectively to form a thermo electric junction as at 46, for example. Following the same general constructional details as presented above, a thermally conductive electrical insulating body 47 as illustrated in FIG. 2 is provided and after the thermal junctions have been soldered to this insulating body 47, the entire device is encapsulated in a material 48, the encapsulating material taking a variety of forms of which any of the embedment plastics would be suitable and if high performance of the switch is desired, then the encapsulation material should be a thermally conductive dielectric, for example, a beryllium oxide filled epoxy.

Referring to FIG. 4 there is illustrated a form of the invention that becomes necessary if one utilizes as the switch an asymmetrical switch in which the contacts are not centered in the capsule or are brought out of the opposite ends of the capsule with two different types of leads such as a solid lead 50 at one end and a tubular lead 51 at the opposite end. Lead material 52, 52' of the same alloy as the reeds connect to an insulator 32' where the thermal junctions with the conductor material 54 are made. This type of switch must be displaced along the axis of the actuating coil 53 until a symmetrical position is found experimentally at which point the thermal EMF across the switch measured at conductors 54 is substantially zero. This is best achieved by having the coil energized so that the same is hot and then manually adjusting the position of the switch until the proper position is found and then securing the capsule switch in position with epoxy or other type of securing compound.

To improve performance and to protect the relays shown in FIGS. 1, 1A, 1B, and 4 from convective air currents and external heat sources the relays should be encapsulated in a suitable material and if high performance of the relay is desired, then the encapsulation material should be thermally conductive, for example, a beryllium oxide filled epoxy.

I claim:

1. A reed relay comprising a coil having an elongated opening, a sealed magnetic switch having an elongated housing, ferro magnetic reeds mounted in said housing and having portions thereof extending therefrom, conductor members electrically connected to said reeds to form connections of dissimilar metals, a body of thermally conductive electrical insulating material, each of said connections being brought into thermal contact with said body and so located as to be electrically insulated from each other whereby the thermally active junctions are maintained at substantially the same temperature and the thermal EMF's produced by the junctions being equal and opposite tend to cancel each other thereby reducing the thermal EMF across the reed relay.
2. A reed relay as in claim 1 wherein lead material identical to the reeds is secured to the reed end portions extending from the housing and extend to the center of the housing exterior at which location the conductor members are secured to the leads.
3. A reed relay as in claim 1 wherein the thermally conductive electrical insulating body is within the elongated opening in the coil.
4. A reed relay as in claim 1 wherein the thermally conductive electrical insulating body is outside the coil.
5. A reed relay as in claim 2 wherein the thermally conductive electrical insulating body is oriented perpendicular to the coil axis.
6. A magnetic reed switch comprising a capsule containing ferro magnetic reeds having portions extending therefrom, conductor members electrically connected to said portions and forming a juncture of dissimilar metals, a body of thermally conductive electrical insulating material, each of the junctures being brought into thermal contact with said body and so located as to be electrically insulated from each other whereby the thermally active junctions are maintained at substantially the same temperature and the thermal EMF's produced by the junctions being equal and opposite tend to cancel each other thereby reducing the thermal EMF across the reed switch.
- 10 7. A magnetic reed switch as in claim 6 wherein lead material identical to the reeds is secured to the reed end portions and extend to the center of the capsule.
